UNITED STATES PATENT OFFICE.

HARRIE A. BALLARD, OF SOMERVILLE, MASSACHUSETTS, ASSIGNOR TO THE BOYLSTON MANUFACTURING COMPANY, OF BOSTON, MASSACHUSETTS, A CORPORATION OF NEW JERSEY.

LOADER FOR HAND-TACKERS.

1,114,330.

Specification of Letters Patent.

Patented Oct. 20, 1914.

Application filed January 10, 1907. Serial No. 351,649.

To all whom it may concern:

Be it known that I, HARRIE A. BALLARD, of Somerville, in the county of Middlesex and State of Massachusetts, have invented 5 certain new and useful Improvements in Loaders for Hand-Tackers, of which the following is a specification.

The present invention relates to an automatic apparatus adapted to contain tacks 10 and to supply them in condition to be used in a hand tacking device. It is intended to be used in connection with a lasting machine, so that actuation of certain parts of the latter will set the loader into operation 15 for supplying tacks to the tacking apparatus, which can be used to secure the edges of the upper after they are shaped over the last by the wipers of the lasting machine.

The invention consists in a tack receptacle 20 which is mounted in connection with a lasting machine, and is constructed so as to permit the insertion and removal of a portion of the raceway connected with a hand tacker, and has means automatically set in 25 operation by the movement of certain of the lasting instrumentalities for supplying the tacks in regular order in the raceway of the tacker so that they can be automatically fed to and driven by the driving members of the 30 latter.

The details of the invention are described and claimed in the following specification, and illustrated in the accompanying drawings, wherein—

Figure 1 represents an elevation of a lasting machine having the preferred embodiment of my tack-loader connected therewith. Fig. 2 represents a rear elevation of the forward part of the loader. Fig. 3 represents a sectional view of the loader, showing in elevation parts of a hand tacker detachably connected therewith in position to receive tacks, that is, to be loaded. Fig. 4 represents a detail elevation of the clearer 35 by which tacks improperly placed on the tacker raceway may be removed. Fig. 5 represents a cross-section of the tacker raceway on line 5—5 of Fig. 3, looking in the direction of the arrow. Fig. 6 represents 40 an elevation of the loader. Fig. 7 represents a section of the same on line 7—7 of Fig. 6. Fig. 8 represents a cross-section on line 8—8 45 of Fig. 6, looking in the direction of the arrow, showing the sprocket wheel and clutch by which the elevating means of the 55 tack-loader is operated.

The same reference characters indicate the same parts in all the figures.

The tack-loader consists in a stationary receptacle 1 mounted upon a standard 2 and 60 having an opening 3 through which tacks may be dropped into the interior thereof. The rear of the receptacle 1 has an annular flange 4 on which is revolubly mounted a tack-holder and elevator 5. The latter is 65 secured to the end of a shaft 6 which extends through a bearing 7 at the top of a bracket 8 connected to the standard 2. On the shaft is secured a clutch member 9 having peripheral inclined notches 10 70 surrounded by a loose sprocket or other driving wheel 11. In the notches 10 between the clutch 9 and driving wheel are balls 12 adapted to be rolled up the inclined sides of the notches and to be crowded thereby 75 against the inner periphery of the driving wheel when the latter is turned in left-hand rotation with respect to Figs. 1 and 8, the driving wheel 11 being movable relatively to the clutch. 80

The loader is adapted to be used in connection with a bed lasting machine of any suitable construction, such a one being shown in Fig. 1, having a frame 13, supports 14 and 15 for a last holding a shoe upper 16, and 85 having also lasting instrumentalities 17 and 18 by which the edges of the upper may be stretched and crimped over the bottom of the last. After the upper has thus been shaped over the last, it is necessary to secure 90 the edges until the sole can be applied, and for that purpose I use a hand tacking device, such as is shown in Fig. 3. The hand tacker is adapted to be detachably engaged with the loader so that it can receive the 95 supply of tacks when not in use, and can be readily disengaged when necessary, for placing tacks in the lasted upper. In order that the tacker may be held where it can be conveniently reached by the operator of the 100 lasting machine, I mount the standard 2 of the loader on a support 19 secured above the rear portion of the lasting machine, and connect the tack-elevating device so that it

will be moved operatively when certain of the lasting instrumentalities are brought into active position.

The operating means consists of the driving sprocket 11 above described, a connecting chain 20, and a sprocket 21 on a shaft 22. The latter extends into the interior of the machine frame and carries a spur gear (not shown) meshing with a rack 23 on the carriage 24 by which the lasting instrumentalities 17 are carried. It will be observed that when the carriage 24 is moved toward the last, the rack 23 turns the wheels 21 and 11 in left-hand rotation, causing connection of the clutch 9 to the wheel, and driving the tack-holder and elevator 5 in left-hand rotation.

As shown in Fig. 7, the holder 5 has internal shelves 25 into which the tacks fall and by which they are elevated when the holder is turned as described. Upon reaching the upper level of the holder the shelves are inclined downward so that the tacks drop out, and fall into a collector 26 from which they are discharged into the raceway of the tacker.

As shown in Fig. 3, the tacker consists of a cylindrical body 27 in which operates a driving plunger 28, and is surrounded spirally by a tack raceway 29. The end 30 of the raceway is straight and tangent to the body 29. It is adapted to be inserted through a slot 31 in the stationary portion 1 of the loader. When inserted, it is detachably held by a latch 32 engaging a transverse bar 33 secured to a lug 34 which is fastened to the body 29. This latch is projected by a spring 35 surrounding the stem of the latch and bearing against a shoulder 37 thereon at one end, and against a bushing 36 screwed into the frame of the loader. A shoulder 37 limits the amount of projection of the latch. A beveled surface 38 adjacent the end of the latch on the side thereof opposite to the opening 31 enables the latch to be depressed by the transverse bar 33 when the raceway is inserted. A trigger 39 is pivoted at 40 to the frame of the loader, and has a slotted arm 41 engaging a pin 42 on the latch. The trigger is mounted in close proximity to the tacker so that when it is desired to remove the latter, the body thereof can be grasped by the hand of the operator, and the trigger pressed by the forefinger of the same hand, whereby the tacker can be released and removed by a single motion of one hand. When the tacker is connected with the loader, its raceway end 30 extends a considerable distance into the interior of the loader at such an angle that gravity will cause the tacks to be fed therein. It lies directly under the lowest portion of the collector 26, which is formed from a plate secured to the stationary part of the loader and projecting well within the inte-

rior of the elevator 5. It is arranged at an inclination substantially the same as that of the raceway end and has inclined plane sides forming a dihedral angle, the latter constituting a central depression in the collector. A slot 43 is cut in the collector on the angle and is of such width that the points of the tacks may project through it, while their heads are supported by the sides thereof. As the tacks fall from the shelves 25, they are arrested by the collector and caused to slide toward the slot. The points of some of them enter the slots and are alined thereby, while the others fall out and return into the elevator. Those which engage the slot are fed downward by gravity into the groove of the raceway.

As shown in Figs. 2 and 5, the raceway consists of two plates 301 and 302, of which the inner side of the latter is partially cut off to provide a tack groove 303. The plate 302 also has a flange 304 extending over the groove to prevent the tacks being thrown out of the latter when a blow is struck on the plunger 28. This covering flange terminates at the point 44 some distance below the end of the collector, so that the slot is uncovered adjacent the latter to receive the tacks fed therefrom. It frequently happens that tacks which are not alined in the slot 43 of the collector lodge crosswise upon the raceway, and upon being arrested by the end 44 of the raceway cover 304, prevent the following correctly alined tacks from continuing down the raceway. Accordingly, to prevent the tacks from so lodging, I provide a clearer which consists of a number of arms 45 mounted on a hub 46 secured to a shaft 47. Slidingly mounted on the arms 45 are dogs or strikers 48 which partially embrace the arms and have ends 49 adapted to extend beyond the ends of the arms. These striker ends 49 are carried from right to left in engagement with the top of the raceway and dislodge the improperly placed tacks. The sliding engagement of the strikers on the arms 45 enables the former to slide along the top of the cover flange 304 and drop below the end thereof. The strikers 48 are prevented from slipping off the ends of the arms by pins 50. On the shaft 47 of the clearer is a pinion 51 which meshes with an idler 52 driven by a circular series of radial teeth 53 on the forward side of the tack elevator 5. By this train of gearing, rotation of the elevator in the direction previously described, turns the clearer in right-hand rotation, as seen in Fig. 3. The collector 26 is detachably secured to the stationary receiver 1 of the loader and is provided at its sides with lugs 54 which are slotted at 55 to engage the shanks of screws 56 threaded into the casing. By means of these lugs and screws, the collector can be quickly connected or disconnected and its

5 inclination can be adjusted. The screws 57 58 shown in Fig. 2 are adjustably mounted in the interior of the loader frame and project toward each other on opposite sides of the raceway. They are designed to center the latter so that the slot thereof will come directly below the slot 43 of the collector.

59 represents an integral shoulder formed on the frame of the tack-loader extending 10 inward over the top of the slot 31. This shoulder acts as a stripper for removing the tacks carried on the raceway above the end 44 of the raceway cover. If these tacks were not removed, they would be dislodged 15 by the vibration of the tacker during its operation and lost. Consequently, when the tacker is disconnected from the loader, it is turned slightly so as to elevate the rear portion of the raceway, and the raceway 20 pressed upward against the shoulder 59. Thereby the upper edge of the raceway slides in contact with the stripper and the tacks above the point 44 are engaged thereby and held back while the raceway is removed. These tacks thereupon drop and 25 are guided into the holder 5.

The periphery of the tack-holder and elevator 5 is provided with spur teeth 60 which mesh with a pinion 61 on the shaft 62 of a 30 wheel 63. This latter has a heavy rim and acts by momentum to continue the motion of the tack elevator after the driving impulse has ceased. Thus when the carriage 24 is moved inward and an impulse is given 35 to the driving wheel, the elevator 5 and wheel 63 are set in motion, and owing to the momentum of the latter wheel, are continued in motion after the carriage has come to rest. This continued motion is permitted by 40 the disconnectible clutch, and thereby the elevator is enabled to furnish an excess of tacks to insure that the tacker will be fully loaded. The fly wheel 63 is grooved externally to receive a belt, whereby it may serve 45 as the driver for the tack elevator when the latter is not directly connected to the lasting instrumentalities.

In order to prevent leakage of the tacks through the slot 31 of the receptacle 1 when 50 the tacker is removed therefrom, I provide the receptacle with a gate 64 which normally covers the slot. The gate is hinged upon a pin 65 (see Fig. 2) which is mounted in a base plate 66. The base is affixed to the interior face of the receptacle so that the gate 55 64 may either cover the slot 31 or swing inwardly to uncover the slot. A spring 67 coiled about the pin 65 and engaging the gate normally causes the latter to cover the slot, but when the extremity 30 of the tack 60 raceway is introduced through the slot it engages and swings back the gate against the tension of the spring.

I claim:—

65 1. A tack-loader having a casing, a tack-

lifting device, said casing having an aperture for receiving the end of a tack-raceway in position to receive tacks from the lifter, a hand tacker to which said raceway is connected, and displaceable means on said casing for engaging and retaining such raceway, said means being located so that it may be engaged by a finger of the hand grasping said hand tacker.

2. A tack-loader comprising a casing having an opening for receiving the end of a tack-raceway, a latch on said loader arranged to engage and retain such raceway when inserted in the loader, a hand tacker to which said raceway is connected; and a finger piece for retracting said latch lying beside said hand tacker when the raceway is in place in position to be operated by a finger of the hand grasping the tacker.

3. A tack-loader having an opening to receive the end of a tack-raceway; a latch; a spring to project said latch across said opening; a hand tacker of a form and size adapting it to be grasped by the hand; a raceway connected to said tacker and arranged to enter said loader; and a finger lever engaged with said latch for retracting it from said opening and located close beside said tacker when the raceway is in place.

4. A tack-loader comprising a casing having an opening to receive the end of a removable tack-raceway; a hand tacker having a raceway attached to it and projecting laterally from it, said raceway having a shoulder; a latch beveled at its end on the side opposite from said opening and arranged to be displaced by said raceway as the latter is inserted in the opening and to engage said shoulder on the raceway after insertion thereof; a spring to project the latch into locking position; and a trigger connected to retract the latch and located beside the body of said tacker so that it may be operated by a finger of the hand grasping the tacker.

5. A tack-loader comprising a stationary portion; a revoluble holder journaled on said stationary portion arranged to receive the tacks put into the latter, and to elevate and then drop them; the loader having provisions for receiving a removable raceway in the path of the tacks falling from the holder; and a rotatable clearer having arms and gravity-operated strikers mounted to slide loosely on said arms adjacent the raceway for removing tacks improperly placed thereon.

6. A tack-loader comprising a stationary casing; a revoluble holder journaled on said casing arranged to receive the tacks and to elevate and then drop them; the casing having an opening for receiving a removable raceway in the path of the tacks falling from the holder; a rotatable clearer journaled in the casing and extending into the interior

thereof adjacent the raceway for removing tacks improperly placed thereon; and driving connections between said holder and clearer, whereby the latter is continuously 5 rotated by the former.

7. A tack-holder comprising a casing having a stationary receiving portion, a revolute tack-elevator; a collector detachably mounted in the stationary portion in position to receive tacks dropped by the elevator, and formed with an angular depression in which a slot is cut, wherein the points of the tacks may enter to aline them, and from the lower end of which they may be fed by 10 gravity; said casing having an opening for receiving the removable raceway of a separable hand tacker and means for holding the said raceway adjacent the slot to receive the gravity-fed tacks therefrom.
- 15 8. A tack-loader having an opening for receiving the end of a hand-tacker raceway; means in the loader for elevating and discharging tacks into the raceway; and fixed means within the loader body and adjacent

the raceway-receiving opening, for stripping 25 tacks from the end of the raceway as the latter is withdrawn.

9. A tack-loader formed with an orifice into which a raceway may be inserted by longitudinal movement, and a gate for covering said orifice, arranged to be displaced by movement of the said raceway and automatically closed upon withdrawal of the raceway.

10. In a tack-loader a revolute clearer 35 comprising arms, strikers mounted slidingly on said arms and embracing the same, arranged to be projected beyond the ends thereof by gravity and to be pushed back upon striking an obstruction, and stops on 40 the arms limiting the amount of projection of said strikers.

In testimony whereof I have affixed my signature, in presence of two witnesses.

HARRIE A. BALLARD.
